UNITED STATES PATENT OFFICE.

UTLEY WEDGE, OF PAOLI, PENNSYLVANIA.

PROCESS FOR OXIDIZING OR CARBONIZING FUEL.

Application filed January 23, 1925. Serial No. 4,179.

To all whom it may concern:

Be it known that I, UTLEY WEDGE, a citizen of the United States, residing at Paoli, in the county of Chester and State of Pennsylvania, have invented a new and useful Process for Oxidizing or Carbonizing Fuel, of which the following is a specification.

The principal object of the present invention is to economically and satisfactorily oxidize or carbonize fuel, including finely divided anthracite or bituminous or lignite coal or other solid carbonaceous fuel either to ash or to coke and in such a way that the process may be carried on continuously, automatically economically, and efficiently.

Other objects of the invention will appear from the following description.

Generally stated, the process of the invention may be said to comprise establishing and maintaining an annular ignited fuel bed to one rim of which fresh fuel is supplied and from the other rim of which solid residue or matter is withdrawn, and impelling the fuel across said bed from one rim to the other rim thereof by the application of mechanical force in generally radial direction from the rim at which the fresh fuel is supplied toward the other rim.

The invention also comprises the improvements to be presently described and finally claimed.

In the following description reference will be made to the accompanying drawings illustrative of the following description of the invention.

In the drawings—

Figure 1 is an elevational view, partly in vertical section, of apparatus adapted for use in the practice of the invention.

Fig. 2 is a sectional view taken on the line 2—2 of Figure 1.

Fig. 3 is a sectional view taken on the line 3—3 of Figure 1 with parts omitted.

Fig. 4 is a sectional elevational view of another form of apparatus adapted for use in the practice of the invention.

Fig. 5 is a like view of still another form of apparatus adapted for use in the practice of the invention, and

Fig. 6 is a plan view drawn to an enlarged scale of one of the parts shown in Fig. 5.

It is a feature of the process of the invention that the ignited fuel of the annular fuel bed is impelled or driven by the application of mechanical force radially across the fuel bed. The ignited fuel may be thus driven by the application of mechanical force radially across the annular bed either toward or away from the center thereof. The ignited fuel of the annular fuel bed is supported against movement by gravity and the mechanical force may be applied to it radially in either direction and at one of its rims by any suitable means. In the drawings I have illustrated the employment of several such means without intending to confine the invention thereto but for the purpose of describing the invention.

Referring to all of the figures there is shown a rotating grate 1, upon which the ignited annular fuel bed is supported.

As shown in Figs. 1 and 2 there is arranged above the grate and at the outside rim of the ignited fuel of the annular fuel bed a wall 2, which may be described as of helical or volute form, and at the center of the annular fuel bed there is a discharge opening 3. The dash and dot line in Fig. 2 is concentric with the grate and is provided to show the volute or helical form referred to. Fresh fuel is supplied at 4 as by the supply device 5, and the revolution of the grate or fuel support 1, in the direction of the arrow in Fig. 2 in co-operation with the wall 2, operates to apply mechanical force to the rim of the fuel bed in radial direction for crowding or impelling the ignited fuel across the fuel bed from the periphery toward the center thereof.

Referring to Figs. 5 and 6, the stationary impellers 2^a between which the fresh fuel is supplied, as at 4^a, by a supply device 5^a, in co-operation with the moving grate are a means for crowding in fresh fuel and for impelling the ignited fuel across the annular fuel bed by mechanical force radially applied. In this case the ignited fuel is impelled by mechanical force across the annular fuel bed from the center outward over the periphery of the grate.

Referring to Fig. 4, the power driven device 2^b is a means for applying mechanical power in radial direction to the rim of the

5 ignited fuel bed as well as a means for supplying and crowding in fresh fuel. In this case the applied mechanical force operates to feed the ignited fuel across the fuel bed toward an opening 3 at the center thereof.

10 In the foregoing description reference has been made to the rotation of the fuel bed in respect to a fixed co-operating element such as 2 or 2^a, but I desire to state that the element 2 or 2^a may rotate in respect to a fixed fuel bed because it is the relative movement that operates to apply mechanical force which impels the fresh fuel and the ignited fuel radially across the bed.

15 For the sake of further description it may be said that in an annular zone adjacent to the fresh fuel feed there is considerable evolution of gas and that in succeeding concentrically arranged and horizontally disposed annular zones the oxidation or carbonization may be carried substantially to ash or it may be carried to coke. One important feature is that the constituents, including the ignited fuel and the fresh fuel 20 in the annular fuel bed are crowded or impelled across the bed by the application of mechanical force to a rim of the fuel bed in radial direction, so that the rate of movement is accurately controllable and controlled. However, and tendency of material 25 to flow or run may, if desired, be restricted and the fuel bed at and near the discharge zone may be kept level by opposing, but not overcoming, the applied mechanical 30 force. One way of doing this is to restrict the discharge of ashes or carbonized material. Referring to Fig. 1, the annular lip 6, when present, retards the travel of the fuel in horizontal direction and opposes its 35 flow in respect to the discharge opening. The rotating ash disc 7, is a means for retarding the escape of ashes and by adjusting its scraper 8 radially the downward movement of the ash column above the disc can 40 be regulated. In Fig. 4 the disc 7 is shown but not the lip 6 of Fig. 1. In Fig. 5 the discharge of ash is not restricted. It may 45 be said that once the fuel is in the ignited fuel bed, the ignited fuel is moved by forces in which gravity plays no substantial part and which are developed by the expenditure of power. The annular fuel bed is disposed 50 generally horizontally and the movement of the fresh fuel once it reaches the fuel bed is generally horizontal, and for that reason the force of gravity plays no substantial part in moving the ignited fuel. In cases 55 where the oxidation is carried to ash, or, in other words, where the fuel is burned, the ash is substantially free from unconsumed carbon and may be quite cool when it is withdrawn from the fuel bed, thus the process is efficient and economical.

60 It will of course be understood that air is supplied to the fuel bed and, as indicated

in the drawings by arrows, this may be done by providing the grate or fuel support 1 with openings.

65 It is an advantage of the present invention that it provides a ring of fire which in many commercial applications is very desirable, for example, in applying heat to the inside surface of the water leg 9 of a cylindrical vertical boiler. Again the center of the ring of fire is comparatively cool, as has been indicated, which is desirable, because, for example, it provides for the use of a support 70 10, to which various fire working tools can be secured without exposure to undue heat.

75 It will be obvious to those skilled in the art to which the invention relates that modifications may be made in details of procedure and in matters of mere form without departing from the spirit of the invention which is not limited as to such matters or otherwise than as the prior art and the appended claims may require.

80 I claim:

85 1. The process of oxidizing or carbonizing fuel which consists in establishing and maintaining an annular ignited fuel bed to one 90 rim of which fresh fuel is supplied and from the other rim of which solid matter is withdrawn, and impelling fresh and ignited fuel across the bed by applying mechanical force 95 to a rim of the fuel bed in generally radial direction.

100 2. The process of oxidizing or carbonizing fuel which consists in establishing and maintaining an annular bed of ignited fuel to the periphery of which fresh fuel is supplied and from the center of which solid matter is withdrawn, and crowding fresh and ignited fuel across the bed by the application of mechanical force radially at the periphery 105 of the fuel bed.

110 3. The process of oxidizing or carbonizing fuel which consists in establishing and maintaining a generally horizontal annular bed of ignited fuel, supporting said bed against movement by the force of gravity, supplying fresh fuel to one rim of the bed and withdrawing residual product from the other rim of the bed, and moving fresh and ignited fuel generally horizontally across the bed 115 by the application of mechanical force to a rim of the bed in radial direction.

120 4. The process of oxidizing or carbonizing fuel which consists in supporting the ignited fuel of an annular fuel bed against movement by gravity, and compelling movement of the ignited fuel radially across said bed by forcing fresh fuel into the bed at one rim thereof and withdrawing solid combustion residue at the other rim thereof.

125 5. The process of oxidizing or carbonizing fuel which consists in supporting the ignited fuel of an annular fuel bed against movement by gravity, and moving the ignited fuel radially across the annular bed by hori-

zontally crowding fresh fuel into the mass of ignited fuel at one rim of the bed and by withdrawing solid residue at the other rim of the fuel.

5. 6. The process of oxidizing or carbonizing fuel which consists in supporting the ignited fuel of an annular fuel bed against movement by gravity, moving the ignited fuel ra-

dially across the annular bed by horizontally crowding fresh fuel into the mass of ignited fuel at one rim of the bed and by withdrawing solid residue at the other rim of the fuel, and keeping the fuel bed level near the discharge zone by restricting the withdrawal of the solid residue.

UTLEY WEDGE.
